UNITED STATES, PATENT OFFICE.

IRA VINCENT COLE, OF SEATTLE, WASHINGTON.

ARROW.

Application filed February 5, 1925. Serial No. 6,946.

To all whom it may concern:

Be it known that I, IRA VINCENT COLE, a citizen of the United States, and resident of Seattle, county of King, State of Washington, have invented an Improvement in Arrows, of which the following description, in connection with the accompanying drawing, is a specification, like characters on the drawing representing like parts.

10 This invention relates to arrows and has for its general object to provide an improved arrow which will fly more accurately than arrows as now commonly made. It is the universal practice to make each arrow with a nock at its heel end to receive the string of the bow when the arrow is being shot, these nocks being in the nature of saw kerfs or grooves of fixed dimensions which are cut transversely across the end of the arrow.

20 The bow strings which are used vary a good deal in size, some bow strings being relatively small and thin and other bow strings having a considerably larger diameter. It is an advantage in shooting an arrow to have the bow string of a size to fit the nock for if the bow string is smaller than the nock there is an opportunity for more or less lateral movement of the arrow when the latter is nocked, a fact which is apt to interfere with the accuracy of the shot when the arrow is loosed. On the other hand, if the string is larger than the nock then in nocking the arrow it is necessary to crowd the string into the nock and, under these conditions the friction between the string and the walls of the nock will place a drag on the arrow when it is loosed thus causing it to fall short.

It is one of the objects of my present invention to provide an arrow with a novel nock which is adjustable so that it will fit strings of different sizes and can be shot with the same effect from a large string as from a small string.

45 Another object of my invention is to provide an improved footing for an arrow which is rugged and will withstand hard usage without breaking and which also gives the arrow the desirable balance.

50 In order to give an understanding of my invention I have illustrated in the drawings a selected embodiment thereof which will now be described after which the novel features will be pointed out in the appended claims.

Fig. 1 is a view of an arrow embodying my invention;

Fig. 2 is an enlarged view partly in section showing the heel end of the arrow having my improved adjustable nock, said figure showing an arrow applied to a relatively small string;

Fig. 3 is a similar view showing the arrow nocked on a larger string;

Fig. 4 is a top plan view of Fig. 3;

Fig. 5 is a section on the line 5—5, Fig. 3;

Fig. 6 is a longitudinal sectional view through the foot of the arrow on the line 6—6, Fig. 7;

Fig. 7 is a top plan view of Fig. 6;

Fig. 8 is a section on the line 8—8, Fig. 6;

Fig. 9 is a section on the line 9—9, Fig. 6;

Fig. 10 is a sectional view similar to Fig. 6 but showing a modification.

1 indicates the shaft or body of the arrow which may be made of any desirable wood and which is provided at one end with the usual feathers 3.

4 indicates the groove or nock in the heel end of the arrow in which the bow string is received when the arrow is being shot. As stated above one of the objects of my present invention is to provide an adjustable nock which will automatically accommodate itself to different sizes of strings.

In the construction herein shown the portion of the end of the arrow forming one wall of the nock is movable toward and from the opposite wall of the nock so as to permit the nock to be varied in width.

The shaft 1 of the arrow is usually made of wood, reed or some similar material and I prefer to make the nock 4 in a nock member 5 of metal which is applied to the end of the shaft 1. This member 5 is shown as having an axial recess 6 into which the end 7 of the shaft 1 fits and said nock member may be secured to the shaft in any suitable way, as for instance by means of rivets 8.

The nock member 5 is formed with the fixed jaw 9 forming one wall of the nock and the movable jaw 10 forming the opposite wall of the nock. Said movable jaw is formed with a fin or extension 11 which is received in a slot 12 formed in the nock member 5 and which is pivotally mounted on the pivot pin 13 that extends transversely through the nock member. This fin is formed at its end with a tail 14 which overlies and is engaged by a spring 15 that occu-

pies the inner end of the recess or groove 12. The spring acts normally to throw the tail 14 outwardly and thus move the jaw 10 toward the fixed jaw 9. This spring-impelled movement is limited by the engagement of the face 16 of the fin 11 with the bottom of the groove 12. The pivoting of the jaw 10 and the action of the spring 15 allows the jaw 10 to swing away from the jaw 9 thus providing a wider nock 4.

The parts will be so adjusted that when the jaw 10 is at the inward limit of its movement the nock will be rather narrower than the average nock of an arrow and will be of a width to fit the smallest string which would be used. Such a string is indicated at 17 in Fig. 2. If the arrow is used with a heavier or thicker string, such as indicated at 18 in Fig. 3, then when the arrow is nocked the jaw 10 will automatically open away from the jaw 9 to receive the string and the arrow will be held in the nock simply by the pressure of the spring 15. The pressure of the walls of the nock against the string, therefore, is substantially the same whether the string is a small string or a large string and, therefore, when the arrow is loosed there is no greater drag imposed on the arrow by the friction of the string against the sides of the nock when it is shot with a bow using a large string than when it is shot with a bow using a small string.

The spring 15 will preferably be a relatively light spring so that the gripping action of the jaws on the bow string will be only sufficient to hold the arrow on the string and will not subject the arrow to any undesirable dragging action when it leaves the string. This automatically-adjustable nock is, therefore, conducive to accurate shooting as the arrow is subjected to the same action when loosed regardless of the size of the string.

In order that an arrow may fly properly it is desirable that it should be so balanced that the center of its weight will be at a point nearer the foot than the heel of the arrow. This fact is frequently secured by providing the arrow with a footing of hard wood which is heavier than that from which the body of the shaft is made. While a footing of this nature answers the purpose so far as getting the desired balance is concerned, yet it has the disadvantage that hard wood is apt to be brittle and an arrow thus made is prone to break if it strikes a rock, target stand or other hard substance. I have provided herein an improved footing for an arrow which not only gives the desired balance but which also is practically indestructible.

My improved footing comprises a tubular metal shell 19 which is inserted over the anterior end of the shaft and is provided

with a solid pointed end. I find that an excellent footing can be made by use of steel tubing although any suitable metal may be used for this purpose. The solid or pointed end may be provided for by inserting a plug 20 into the end of the tubing. The tubing herein shown is provided with diametrically opposite V-shaped slits 21 which extend from the inner toward the outer end of the tubing and which form the two wings 22. This footing may be secured to the arrow by means of rivets 23 extending through the wings. With this construction the rivets 23 when properly inserted draw the wings 22 tightly against the shaft 1 so as to provide a close fit between the shaft and the wings regardless of any variation in the size of the shaft.

I will preferably so shape the portions 24 of the shaft which the wings overlie that they fit the interior of the wings so that the arrow will have a circular cross section through the foot portion and the wings will come flush with the surface of the shaft so as to make a smooth exterior surface.

If desired, I may make the shaft of the arrow with the tapered insert 25 of a hard wood heavier than that from which the body of the shaft is made thereby to give the required weight to the foot end of the arrow without the use of so much metal. The employment of the tubing 19 with the relatively long wings 22, however, adds a very desirable element of strength to the arrow and prevents the liability of the foot becoming broken upon striking a solid object.

While I have illustrated herein a selected embodiment of my invention I do not wish to be limited to the constructional features shown.

I claim.

1. An arrow provided with a shaft having a nock adjustable as to its width.
2. An arrow provided with a shaft having a nock automatically adjustable as to its width.
3. An arrow having a feathered shaft and provided at its end with a nock, portions of the arrow forming the opposed walls of the nock, being movable relatively toward and from each other.
4. An arrow comprising a feathered shaft, a nock member secured to the end of the arrow and formed with a nock, the portion of said member constituting one wall of the nock being movable toward and from the opposite wall.
5. An arrow having a feathered shaft, a nock member secured to the end of the shaft, said nock member presenting two jaws forming between them the nock, one of the jaws being movable relative to the other.
6. An arrow having a feathered shaft, a nock member secured to the end of the shaft, said nock member presenting two jaws

forming between them the nock, one of the jaws being pivotally mounted and swingable toward and from the other.

7. An arrow having a feathered shaft, a nock member secured to the end of the shaft, said nock member presenting two jaws forming between them the nock, one of the jaws being pivotally mounted and swingable toward and from the other, and a spring acting on the pivotally mounted jaws and adapted to press it yieldingly against the bow string when the arrow is nocked.

8. An arrow comprising a feathered shaft having a nock at its feathered end and a tubular metal foot member fitted over the anterior end of the shaft, said foot member presenting two opposed wing portions which overlie the opposite sides of the shaft.

9. An arrow comprising a feathered shaft having a nock at its feathered end and a tubular metal foot member fitted over the anterior end of the shaft, said foot member presenting two opposed wing portions

which overlie the opposite sides of the shaft, 25 and a plug closing the end of the foot member and constituting the point of the arrow.

10. An arrow comprising a feathered shaft comprising a nock at one end, an insert of relatively heavy wood set into the opposite end and a metal footing encircling 30 said end, and comprising a cylindrical portion in which the extremity of the shaft is received, and two wings overlying the opposite sides of the shaft.

11. An arrow comprising a feathered 35 shaft comprising a nock at one end, an insert of relatively heavy wood set into the opposite end and a metal footing encircling said end and comprising a cylindrical portion in which the extremity of the shaft is 40 received, two wings overlying the opposite sides of the shaft, and rivets connecting the wings and extending through the shaft.

In testimony whereof, I have signed my name to this specification.

IRA VINCENT COLE, M. D.
